UNITED STATES PATENT OFFICE.

HORACE W. JANICKE, OF BERKELEY, CALIFORNIA.

CAMPING OUTFIT FOR AUTOMOBILISTS.

Application filed December 21, 1926. Serial No. 156,155.

This invention relates to camping outfits for automobilists and has for its primary object the provision of a new and useful combination of parts adapted normally to 5 constitute a complete compact package that may be carried trunk-like by an appropriate part of an automobile and arranged for quick accessibility when needed and the parts separated relatively and adjusted to 10 certain forms to constitute articles of campers' furniture, such as a set of stools, a table, and a storage receptacle for articles of food.

Another object of the invention is to provide a device of this character wherein all 15 parts or adjuncts thereof may be quickly set up or knocked down as the occasion requires.

A further object of the invention is to provide a device of the character whose 20 parts may be nested or telescoped together and the whole secured to the automobile or vehicle as a single unit and in such manner as will prevent the accidental loss of any of the parts in transit.

25 A still further object of the invention is to provide a device of this character which will be ornamental and attractive when applied to an automobile.

A further object of the invention is to 30 provide a device of the character wherein a large number of articles of furniture can be arranged to form a complete package of minimum size but wherein each article will be of maximum strength and durability.

35 With the above and other objects in view, which will appear as the nature of the invention is better understood, the same consists in the improved construction and novel arrangements of parts which will herein- 40 after be fully described and particularly pointed out in the claims.

In the accompanying drawings has been 45 illustrated the preferred form of the invention, it being, however, understood that no limitations are necessarily made to the precise structural details therein exhibited, but that changes, alterations and modifications within the scope of the claims may be resorted to when desired.

50 Figure 1 is a perspective view of the device set up for use;

Figure 2 is a perspective view of the device knocked down and folded in normal arrangement, with parts broken away and 55 parts shown in section for the purpose of clearness;

Figure 3 is a somewhat inverted perspective view of the table partly set up;

Figure 4 is a bottom plan view of a portion of the table;

Figure 5 is a view in end elevation of the food receptacle;

Figure 6 is a section on line 6—6 of Figure 5;

Figure 7 is a section on line 7—7 of Figure 6, and

Figure 8 is a view in side elevation of one of the folding stools.

Figure 9 is a view in perspective of portions of one of the leg braces.

In carrying the invention into practice, use is made of articles of furniture A, B and C, the latter including a group of stools, preferably four in number, of which two are of the collapsible or folding type, and the others of a permanent, non-folding type, which are adapted to be telescoped with respect to other parts of the invention in a manner and for a purpose to be hereinafter described.

The article of furniture A comprises a receptacle having a base portion 10 formed with extensions 11 adapted to be secured by fastenings 12 to a suitable support of an automobile or vehicle, such as a running board or other appropriate exterior part thereof. It may be carried at the rear portion of an automobile, which I deem the most likely or practical place of application, because when all of the articles of furniture 90 A, B and C are nested together as a complete unit, the entirety appears trunk-like, where the device lends to the graceful appearance of the body of the automobile. The said receptacle is formed with a vertical wall 13, end walls 14—14, a hinged top or closure wall 15, and a hinged shelf-forming section 16 adapted when adjusted to the position shown in Figures 1 and 5 of the drawings to provide for the forming of an opening 17 at one side of said receptacle.

The said shelf wall 16 is formed with side wings 18 having lugs 19 mounted to operate in arcuate recesses 20 in said end walls 14, and to engage with the upper abutments 105 20^a of said recesses, so as to limit movement in one direction of said shelf and cause same to be supported in a relatively rigid, horizontal plane, as shown in full lines in Figure 5. Hinged at 21 to the said wall 13 110 is a wall 22 having end walls 23, connected therewith, a top wall 24, and a front wall

or closure 25, the latter hinged at 26 to one edge of said wall 24 as shown in Figures 1 and 5. In this manner there is formed a second receptacle 27 which may be superposed with respect to the said base section as also shown in Figures 1 and 5, likewise Figures 6 and 7, of the drawings. The hinge 21 extends for a distance slightly beyond the ends 14-14 of the underlying receptacle, so that when the cover section 25 is swung back upon the wall 24, the said top section 27 may be folded upon the lower section, the latter becoming nested in the former. In effecting such adjustment of the 10 said upper section, the walls 22 are adapted to freely slide over the outer faces of the walls 14-14 of the lower section, as is endeavored to be indicated by the dotted line showing in Figure 7. When the upper section 15 is thus folded, the closure 25 assumes a vertical position at one side of said lower section 10. When the upper section 27 is adjusted to the full line positions shown in Figures 1, 5 and 6, pivoted brackets 28 on 20 the lower edges of the walls 23 are swung around to traverse the walls 14-14 of the lower section 10 and to rest upon said upper edges of these walls, thus holding the upper section 27 against turning on its hinge 21. 25 When the closure wall 25 is swung down to its full line position shown in Figures 1 and 5 of the drawings, pivoted latch device 29 may be projected through slots 30 in the closure 25 to hold the latter in a position of closed adjustment. The upper section has its end walls and the closure 25 formed with openings 31 covered by wire gauze, 32, or other suitable material, so as 30 to allow for atmospheric ventilation of said upper section.

Normally, articles of food may be stored in the lower section 10, and when it is desired to partake thereof after the camping equipment has been set up for use, same can 35 be transferred into the upper receptacle section 27 where it will be held against contamination by insects, and in a fresh, ventilated state where access can be gained thereto whenever desired.

40 The article of furniture B is in the form of a table of the folding-leaf type, three leaves, 32^a, 33 and 34 being employed and joined together by suitable hinges 35. The intermediate leaf 32^a is provided at its respective ends with metallic flanges 36, each provided near its lower corners with perforations 37 for a purpose to be herein-after explained. At each corner of the table 45 is a supporting leg 38, two of which are employed in connection with each of the leaves 33 and 34, and same are shown as hinged at 39 to the respective outer corners of these leaves. The hinge 39 at one corner of each 50 leaf is offset laterally with respect to the portion of the hinge at the opposite corner

of the same leaf, so that the two legs of each leaf can be swung down to occupy side by side positions as clearly shown in Figure 4. The purpose of this arrangement will appear as the description goes forward. 55 Each leg is provided with a prop 40 consisting of mating links 41 and 42, the latter pivoted at 43 to its leg, and the former at 44 to its leaf. The two links are pivotally joined together at 45 and, as shown, the link 42 is formed with a notch 46 to accommodate a stop lug 47 on the link 41, whereby to limit movement of the two links in one direction and to serve against accidental breaking of the joint between the links when the leg is 60 set up. Each leg is provided with a retention device 48, pivoted at 49 to the leg and provided with spaced apart lugs 50 normally seated in apertures 51 in the leg, and adapted when the device is pulled out from the leg at the lugs 50, to be swung on its pivot 49 so that they may be brought into the apertures 37. The entire table is then in a comparatively rigid state when set up to the position shown in Figure 1. It will 65 serve in the customary manner of a table to support ordinary weight that would be placed upon it.

The articles of furniture C consist preferably of two stools of the type shown at 52 and two stools 53 of a relatively rigid type. Each stool 52 comprises a canvas seat 54 connected at its respective ends to the cross bars 55 of bracing and stretching frames 56 and 57, pivoted together at 58 so that 70 one frame may be folded inside the other as shown in Figure 8, where the seat is reduced into a comparatively flat package, capable when folded of being placed in a clip 59 on a companion end-leaf of the article of furniture B. The stools 53 each consist of an open side 60 and an open bottom 61, bounded by side walls 62, 63, 64, and an end wall 65.

The construction of the article of furniture B is such that it can be folded so that the leaves 33 and 34 will hang down from the leaf 32^a, as shown in Figure 2, so that when thus arranged the table is made to telescope the article of furniture A when the latter is collapsed and folded in the manner hereinbefore specified. When the table is arranged in this manner over the folded article of furniture A, the two stool sections 53 are arranged end to end with their openings 61 confronting one another. They are made to telescope over the folded articles of furniture A and B, as clearly illustrated in Figure 2. The entire device then takes the form of a trunk, and for this reason the stools 53 may be made in imitation of leather and provided with ornamental corner pieces 66. The extensions 12 are provided with swinging bails 67 which carry straps 68. One of these straps is formed with a buckle 70

69 to adjustably receive the free end of the other strap. Both straps are now free for adjustment where they can be brought into tight binding engagement with the stools
5 53 that comprise the outer housing. The upper ends of the bails are formed with hand grips 70 in order that they can be freely manipulated when desired.

When the articles of furniture A, B and
10 C are correlated as herein set forth, they all come within a space of very minimum proportion, and it is with astonishment that these articles may be so conveniently separated relatively and set up into an after-
15 wards apparent bulky mass of useful furniture. The process of knocking down or setting up the respective articles can be done with utmost dispatch. On reference to Figure 7 it is observed that the lower re-
20 ceptacle section 10 is always free to be used for the purpose of storing articles of food or other matter.

While I have shown only the preferred form of the invention, it should be understood that various changes or modifications may be made within the scope of the claims hereto attached without departing from the spirit of the invention.

I claim:

30 1. A collapsible camping outfit comprising a receptacle having two compartments,

one compartment being adapted to telescope within the other compartment, a table having a top composed of three sections foldable so as to receive said receptacle when the latter is collapsed, folding chairs removably carried by certain of said table sections and rigid stools adapted to house said receptacle and said table when said receptacle and said table are collapsed.

2. In a device of the type described, a table having a top formed of three sections, foldable legs carried by the outer sections of the table and means for securing said legs in operative position, said means including bracing devices carrying lugs, and reinforcing members carried by the center section and having openings for receiving said lugs whereby the legs are supported in operative position and the center section is prevented from sagging.

3. In a device of the type described, a receptacle having two compartments therein, one of said compartments being receivable in the other, the lower compartment having a movable wall constituting a swingable shelf, said wall when open, permitting access to the lower compartment, the upper compartment having a hinged wall swingable over a fixed wall for permitting the telescoping of the compartments.

HORACE W. JANICKE.
